(57) **CLAIM**

The ornamental design for a miniature golf hole as shown and described.

DESCRIPTION

FIG. 1 is a front perspective view of a miniature golf hole showing our new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is an additional front perspective view thereof, showing the miniature golf hole of FIG. 1 with an overhang. The broken lines in the figures show portions of the miniature golf hole that form no part of the claimed design.

1 Claim, 7 Drawing Sheets
